(57) **CLAIM**

The ornamental design for a counting stamping apparatus, as shown and described.

DESCRIPTION

FIG. 1 is a front elevational view of a counting stamping apparatus showing our new design, the rear elevational view being identical;

FIG. 2 is a side view, taken from the left side of FIG. 1, the right side view being identical;

FIG. 3 is a top plan view thereof; and,

FIG. 4 is a bottom plan view thereof.
